UNITED STATES PATENT OFFICE

ARCHIBALD JOHN HALL, OF BUGLAWTON, ENGLAND

DYEING MACHINE

Application filed November 14, 1929, Serial No. 407,178, and in Great Britain November 30, 1928.

This invention relates to means for collecting and disposing of steam, vapours, fumes, gases, and the like which may be discharged from dyeing machines.

- 5 In the dyeing of textile materials, such as loose fibres, yarns, hose and fabrics, it is usual to immerse such materials in a hot or boiling dye liquor which is agitated or circulated relative to the material being dyed. Such motion of the dye liquor is necessary for the even dyeing of the textile materials, and may be produced by various methods. In certain types of modern dyeing machines, it has been found preferable 15 to agitate or circulate the dye liquor by blowing into it air or a mixture of air and steam. When air alone is used it is usual to use an air compressing machine, and when a mixture of air and steam is used it is usual to obtain and force this mixture 20 into the dye liquor by means of an "air-steam injector." This last-named injector is a device well known to engineers and the makers of dyeing machines, and is constructed such that steam being blown into 25 the dye liquor passes through a nozzle and thus draws air from the outside atmosphere so that a mixture of air and steam enter the dye liquor. It will be readily understood 30 that during dyeing a considerable quantity of steam or water vapour is discharged from the dyeing machine into the surrounding atmosphere, and that this discharge is very objectionable.
- 35 According to the present invention, the open top of the dye vat is provided with a hood or cover having a pipe or the like connection to means for exhausting air, steam or vapour therefrom. Conveniently, this connection may be made to the inlet for the injector, so that there will be a continuous 40 re-circulation of air, steam or vapour.
- By this means any discharge of air, steam or vapour into the atmosphere of the dye 45 house is avoided, and in view of the re-circ-

culation of such air, gas or vapour, an increase in heat efficiency is obtained.

The invention will be more particularly described with reference to the accompanying drawing showing one form of arrangement in perspective.

The dye vat 1 is provided at or towards its base with a perforated pipe 2 from which air or steam may be forced for the circulation of the dye liquor or goods or both in 55 the vat 1.

The air or steam injection or air and steam injection may be effected by means of an injector 3 connected to a source of steam 4. This injector 3 is provided with an air 60 inlet 5 and also a connection 6 to the vat 1 or to a hood 7 upon it, so that air, steam or vapour from above the dye liquor in the vat 1 will be drawn off and re-circulated 65 through the said liquor.

Windows 8 in the hood 7 are preferably provided to allow for inspection of the action within the vat.

Means may be provided, if desired, to adjust the inflow through the air inlet 5 or 70 through the connection 6 or both.

Means may be provided at 9 for allowing an escape to waste of a small proportion of the mixture of air and steam passing from the injector to pipe 2 in the dye liquor, so 75 that the volume of air and steam drawn by the injector out of the machine is slightly greater than the volume of mixture injected into the machine. The difference between the drawn out volume and the injected volume is made up by the leakages of the joint 80 between the hood and the tank. This increases the efficiency of the hood as air is thereby drawn into the machine and no mixture of steam and air is expelled through 85 the joint between hood and machine. A small pipe can be fixed to lead the waste through 9 outside the building.

I declare that what I claim is:—

An apparatus for treating textile mate- 90

rial, comprising a vat, a closed cover thereon, an inlet pipe towards the bottom of said vat, the outlet pipe towards the top of said vat, a connecting pipe between said outlet and inlet pipes and means connected to said connecting pipe to provide a continuous air or gas circulation therethrough, and a further connection to said connecting pipe to allow a proportion of air or gas to flow to waste.

10 In witness whereof, I have hereunto signed my name this 2nd day of November, 1929.

ARCHIBALD JOHN HALL.
